UNITED STATES PATENT OFFICE.

MARION H. KERNER, OF NEW YORK, N. Y.

DESIGN FOR A PAPER-CUTTER.

SPECIFICATION forming part of Design No. 16,843, dated August 10, 1886.

Application filed May 9, 1886. Serial No. 291,611. Term of patent 7 years.

To all whom it may concern:

Be it known that I, MARION H. KERNER, a citizen of the United States, and a resident of New York, in the county and State of New York, have invented and produced a new and original Design for Paper Cutters or Folders, of which the following is a specification.

The design principally consists of a paper cutter or folder formed with a blade at each end, and with an enlarged or raised central portion between them and on one side of the cutter or folder, the opposite side being flat. This enlarged portion of the cutter or folder is thickest at its center, from which point it is gradually curved or tapered to the blade portions. The blades flare slightly outward in width near their ends, and gradually decrease in width toward the center of the cutter or folder.

In the accompanying illustrations, which represent the design, Figure 1 is a perspective view; Fig. 2, a cross-sectional view on the

lines 4 4; and Figs. 3 and 4 represent cross sections on the lines 3 and 2, respectively.

In the illustrations, A represents the enlarged or raised central portion, and *a a* the blade portions. The blades *a a* are pointed at their ends, as shown.

What I claim is—

The design herein set forth, consisting of a paper cutter or folder formed with the enlarged or raised central portion, A, on one side, (the opposite side being flat,) and having a blade portion, *a*, at each end, said blades being widest at their outer ends and tapered or of gradually-decreasing width toward the center, substantially as shown and described.

In testimony whereof I have signed my name, in presence of two witnesses, this 5th day of May, 1886.

MARION H. KERNER.
